Assistant Examiner—Jeffrey Asch

[57] CLAIM

The ornamental design for a fashion pocket insert, as shown and described.

DESCRIPTION

FIG. 1 is a front elevational view of a fashion pocket
insert showing my new design;

FIG. 2 is a right side elevational view, the left side being a mirror image thereof; and

FIG. 3 is a rear elevational view thereof.
